UNITED STATES PATENT OFFICE.

JULIUS F. HANSEN, OF EVANSTON, ILLINOIS, ASSIGNOR TO THE DOLLAR SAVING AND TRUST COMPANY, OF YOUNGSTOWN, OHIO, A CORPORATION OF OHIO.

TUBE-BENDING MACHINE.

1,261,229.

Specification of Letters Patent. Patented Apr. 2, 1918.

Application filed August 19, 1915. Serial No. 46,233.

To all whom it may concern:

Be it known that I, JULIUS F. HANSEN, a citizen of the United States, residing at Evanston, in the county of Cook and State 5 of Illinois, have invented certain new and useful Improvements in Tube-Bending Machines; and I do hereby declare the following to be a full, clear, and exact description of the invention, such as will enable others 10 skilled in the art to which it appertains to make and use the same.

My invention relates to machinery for bending tubing and more especially for the bending of metal pipes or tubes.

15 One of the objects of my invention is to improve the machine illustrated in the application of Charles Vallone, No. 7578, series of 1915, filed Feb. 11th, 1915, by providing more facile, convenient and economical 20 means for preventing disfiguration of the tubing in bending.

This and other objects of my invention will probably be better understood from a description of an embodiment of the invention. 25

Figure 1 of the drawing shows a plan view of a machine embodying my invention, with a portion of the apparatus shown in section.

30 Figs. 2, 3, 4, and 5 are sections upon the lines O—2, O—3, O—4 and O—5.

Fig. 6 shows the embodiment illustrated in Fig. 1 with the bending members in position after the wheel has been turned through 35 the desired angle.

Referring now to the drawing, and to the embodiment illustrated therein at 9 is shown a base supporting the mechanism for bending the tube. At 10 is shown a tube bending member, preferably having a curved surface of whatever character desired, and here shown as a circular wheel. The member 10 is mounted upon a shaft 11 supported vertically in the frame in any suitable manner, the wheel being fastened to the shaft by any suitable means, which may include a nut 12. The tube is bent about the member 10 in the embodiment illustrated. Means are provided for transmitting power to the bending member 10 to move the same. In the embodiment of my invention illustrated, this means includes a gear wheel 13, which is also mounted upon the shaft 11 and rigidly fastened thereto. A shaft 14 is pro-

vided with a worm gear 15, which engages 55 teeth upon the gear wheel 13. The shaft 14 is mounted in any suitable manner in the frame, such as in a bearing 16.

A gear wheel 17 is mounted upon the shaft 14, which meshes with a second gear 60 wheel 18 upon a third shaft 19 mounted in the frame in any suitable manner, such as in bearings 20. A pulley 21 is mounted upon the shaft 19. The pulley is driven, for example, through a belt by a dynamo, engine, 65 or other prime mover. The rim of the bending wheel 10 is provided with a groove 22, cut in the periphery thereof, leaving flanges 23 at the sides of the groove. This groove should be cut to fit the contour of the outer 70 surface of the tube which is to be bent.

In the form illustrated, the mechanism is arranged for the bending of cylindrical tubing. The grooves would, therefore, be semi-cylindrical in section on planes taken 75 through the long axis of the shaft 25. The apparatus is also arranged for bending the tube in some desired arc of a circle, and therefore, the portion of the bending wheel engaging the tube is an arc of a circle. The 80 apparatus is also arranged to bend the tube through an arc of ninety degrees. It will be appreciated that the apparatus may be so arranged as to operate upon tubes of any character and to bend them in any desired 85 length and shape of arc, without departing from the spirit of the invention.

A mandrel 30 is provided, which is mounted in the interior of the tube, and over which the tube is bent. The special form 90 and shape of the mandrel itself constitutes no part of my invention, though it is preferable to employ some mandrel of suitable shape, such that bending can be correctly and easily performed. The mandrel 30 is 95 provided with a nose 32 and a main portion 31. The mandrel is supported by some suitable supporting means, such as a rod 40 extending through the tubing connected in any suitable manner at 41 to the mandrel. 100 Means are provided for grasping one section of the tube, here shown as a pair of clamp grips 42 and 43. The grip 43 may be integral with the bending wheel, as illustrated in the drawing. The clamp 42, however, is preferably made separate from the other parts, in order that it may be removed or swung clear of the clamp 43 when 105

the tube is to be inserted or removed. The parts 42 and 43 may be provided with grooves 44 and 45, respectively, of such contour that the tube is tightly gripped between the members 42 and 43. In the form shown the grooves in the members 42 and 43 would, of course, be semi-cylindrical in cross-section. Any suitable means may be provided for clamping the members 42 and 43 together, such as a bracket 46 and a clamping screw 47. Means are also provided for holding another section of this tube, but preferably permitting longitudinal movement thereof, the tube being permitted to slide longitudinally when bent. This means consists of a follower 49, which is positioned upon the frame by any suitable means, in such a manner as to conveniently perform its functions. The member 49 is provided with a groove 51 into which the tube fits, and in which it is positioned. The member 49 also serves as an anvil or backing member when the lug 200 engages the tube.

When the tube is bent, the follower 49 moves with the tube as it is drawn through the frame, the follower being held against the tube by a clamping arrangement 52. Means are provided for pressing out any deformities, such as kinks or other irregularities which appear in the under-side of the tubing at the conclusion of the bending movement. In the form shown, this member is formed by carrying the portion 222 of the groove 22 from a point 201 rectilinearly and in a direction tangential to the groove 22. In other words, in the specific structure of the embodiment illustrated, the groove 22 in the wheel is of substantially the same arc as that desired to be given to the tube and the groove is extended rectilinearly at each end of said arc, so as to be tangential to the groove 22. In the embodiment illustrated the tube is to be bent through 90° and the arc from the point 201 to the point 101 is 90°.

It will readily be appreciated that as the tube is bent, there will be a tendency for the inner portion of the tubing to crimp or crease, especially that portion which is not drawn into contact with the walls of the groove in the wheel. The part 200, however, (as shown in Fig. 6) engages this portion of the tube at the conclusion of the operation and effectively presses out any irregularities in the walls of the tube between the body portion 31 of the mandrel and the part 200. A spring 90 is connected at one end 91 to a bracket 92 supported in the frame and at the other end 93 to a hook 94 on the follower. This spring is expanded when the wheel is operated and acts to return the follower when it is released.

The operation of my device will be ap-

parent from the description. The wheel 10 being rotated, the end of the tube engaged by the members 42 and 43 will be carried clockwise from the position shown in Fig. 1 to the position shown in Fig. 6, the tube being drawn over the wheel and bent over the wheel and mandrel, the member 49 following the tube as it is bent to the position shown in Fig. 6. Those portions of the tube which pass over the periphery of the wheel 10 will be properly ironed out, so to speak, and at the conclusion of the operation, the part 200 will engage the outside of the surface of that portion of the tube adjacent the underside of the mandrel 30 and press out any irregularities which have been caused in this portion of the tube by the bending thereof.

It will be understood that I have employed these forms and these details for the purpose of illustrating my invention, and that I do not wish to be limited thereto, as many variations may be made in the forms and details and many departures made from those illustrated in the drawing, without departing from the spirit of the invention.

I claim:

1. In a tube bending machine, the combination of a bending wheel provided with a peripheral groove, a mandrel mounted concentric with the groove, there being space enough between the walls of the groove and the mandrel for the wall of the tube to be bent, a lug in the rear end of the groove integral with the wheel and having a groove therein tangential to the peripheral groove and mechanism to rotate the wheel and cause the lug to engage the portion of the inside of the tube at the end of the bend and iron out any irregularities therein against the mandrel.

2. In a tube bending machine, the combination of a bending wheel provided with a peripheral groove, a tube straightening lug on said wheel at the end of said groove, said lug being provided with a groove tangent to the groove in the wheel, mechanism to bend a tube about said wheel, and means within the tube against which the lug at the end of the stroke presses a portion of the tube eliminating any irregularities therefrom.

3. In a tube bending machine, the combination of a bending wheel provided with a curved peripheral groove of substantially the same arc as the angle to be given the tube to be bent and having a cross-sectional area substantially half the cross-sectional area of the tube to be bent, said wheel provided with a second and straight groove in its periphery of substantially the same cross-sectional area as the first groove and tangential therewith, whereby a tube engaging lug is formed on said wheel at the end of the peripheral groove, a mandrel having sub-

stantially the same sectional shape as the bore of the tube to be bent, means to hold the mandrel in the bore of the tube to be bent adjacent the wheel, an anvil in said machine on the opposite side of the mandrel from the wheel, said lug engaging a portion of the tube at the end of the part of the tube curved by the machine and eliminating any irregularities therein by pressing same against the mandrel and mechanism for operating said wheel.

In witness whereof, I have signed my name this 11th day of August, 1915.

J. F. HANSEN.
